UNITED STATES PATENT OFFICE

FRANK P. J. PATENALL, OF BALTIMORE, MARYLAND.

RAILWAY-SIGNAL-OPERATING MECHANISM.

No. 802,590.

Specification of Letters Patent.

Patented Oct. 24, 1905.

Application filed February 24, 1905. Serial No. 247,135.

To all whom it may concern:

Be it known that I, FRANK P. J. PATENALL, a citizen of the United States, residing at Baltimore, in the State of Maryland, have invented certain new and useful Improvements in Railway-Signal-Operating Mechanism, of which the following is a specification.

My invention relates to railway-signal-operating mechanism, and particularly to visual signals. By the term "signal" as used herein I mean to include any visual signal device which by its color or by its position relatively to its support will give indication of the service condition of the railroad-track or section of railroad-track which it governs.

I will describe a signal-operating mechanism embodying my invention and then point out the novel features thereof in claims.

In the accompanying drawings, Figures 1, 2, and 3 are elevations of two semaphore-signals with operating mechanism embodying my invention for moving each signal to two positions, the signals being shown in different positions in each figure. Figs. 4, 5, 6, and 7 are elevations of two semaphore-signals with operating mechanism (partly in perspective for the sake of clearness) for moving one of the signals to three positions and the other to two positions, the signals being shown in different positions in each figure. Figs. 8, 9, 10, 11, and 12 are similar views of two semaphore-signals with operating mechanism for moving each signal to three different positions, the signals being shown in different positions in each figure.

The broad idea contemplated by my invention is to operate a plurality of signals by a plurality of levers with a single line of connections between the levers and the signals and the levers being at all times operatively connected to the signals.

Referring now to Figs. 1, 2, and 3, A is a signal-post, and B B' two semaphore-signals pivoted thereon in the usual manner and provided with the usual counterweights b, which tend normally to hold the blades in danger position. C and C' indicate two angle-levers for operating the signals, which levers are to be pivoted at their angles e upon suitable supports. (Not shown.) It is to be understood that these levers will be provided with means for locking them in any position to which they may be moved. For instance, they may be provided with a latch adapted to engage notches in a quadrant in a well-known man-

ner. These details of construction, however, form no part of the present invention and are not illustrated in the drawings, it being only necessary to show the levers and other parts of the operating mechanism in the positions they assume in the operation of the signals. It is also to be understood that suitable supports and guides will be provided for any other parts of the operating mechanism wherever they may be necessary. d and d' indicate bell-crank levers connected, respectively, to the short arms of the levers C and C' by rods e and e', the connections being such as to make the bell-crank levers act in opposite directions.

f and f' are rack-bars connected, respectively, to the crank-levers d and d', and their racks are engaged with a floating pinion g on opposite sides thereof. To the pinion g a rack-bar h is journaled, and its teeth engage pinion i, supported to rotate near the post A. This pinion i is also engaged by a vertically-extending rack-bar j, the pinion i being wide enough to engage both rack-bars h and j. The upper end of the rack-bar j is pivotally connected to a floating lever k substantially midway its ends, and one end of this lever is connected by a rod l with the counterweight b of the signal B, and the other end of said lever is connected by a rod l' to the blade of signal B'. When the parts are in normal position, as in Fig. 1, the floating lever k will preferably be inclined from the horizontal, as shown, the end connected to the counterweight b of the signal B.

This apparatus will operate as follows: To lower the signal B to indicate "safety," the lever C will be pulled from the position shown in Fig. 1 to that shown in Fig. 2, or substantially such position, and this will operate the crank d and cause it to push the rack-bar f toward the post A, and since the rack-bar f' cannot move on account of lever C' being locked in position the pinion g will travel with the rack f, and thereby cause the rack-bar h to turn the pinion i, which in turn will by its engagement with the teeth of the rack-bar j cause the latter to move upwardly, and since the signal B' cannot be moved upwardly the joint between the lever k and rod l will become a fulcrum for the lever k, and the end connected to the rod l will move up to the position shown in Fig. 2, and thereby move the signal B to indicate "safety." By restoring the lever C to its normal position the sig-

nal B will be returned to normal position without affecting the signal B', for while the downward pull on the lever *k* will have a tendency to shift signal B' it will, in fact, not affect it, as the resistance of the counterweight of the signal B' will oppose such movement, while the counterweight *b* of the signal B will assist the return movement of its signal to danger position. To move the signal B', the lever C' will be operated, and the action will be substantially the same as already described, except that the rack-bars *f'* and *h* will move toward the levers C and C', and the rack-bar *j* will move downwardly and exert a pull on the lever *k* and rod *l*, the joint between the lever *k* and rod *l* being the fulcrum for the lever *k* in this instance.

Referring now to Figs. 4, 5, 6, and 7, the connections between the lever C and the signal B are the same as heretofore described and operate in the same manner. The connections from the signal B' are also the same to the rod *e'*; but in this case instead of connecting this rod directly to a lever, as C', it is connected to a floating lever *d'*, about midway the length of the latter, and two levers D and D' are employed, being connected, respectively, to the ends of the floating lever *d'*. In this arrangement the signal B is intended to be moved to two positions only, as in Figs. 4 and 5. The signal B' is, however, designed to be moved to three positions, as in Figs. 5, 6, and 7, to indicate "danger," "caution," and "safety." To move the signal B' to the position shown in Fig. 6 from that shown in Fig. 5, either of the levers D or D' may be moved (D', as illustrated) to the position shown in Fig. 6, and as the lever D is locked against movement the joint between it and the floating lever *d'* will become a fulcrum for the lever *d'* and the end thereof connected to the lever D' will be lifted, and thereby cause the rod *e'* to move the crank *d* to the position shown in Fig. 6, which will result in moving the racks *f'*, *h*, and *j* and the signal B' to the positions shown in Fig. 6. The lever D can next be pulled back to the same position as D', and now the joint between lever D' and floating lever *d'* becomes the fulcrum for the latter, and the end of the lever connected to the lever D is lifted up, which results in moving the rod *e'* and all the other connections between it and the signal B' to the positions shown in Fig. 7, by means of which the signal B' is moved to the safety position.

Referring now to Figs. 8, 9, 10, 11, and 12, the connections from the signal B' to the levers D and D' are the same and operate in the manner just described with reference to Figs. 4, 5, 6, and 7. In this case the signal B is also a three-position lever, and instead of the rod *e* being connected to a single lever C, as in the figures previously described, it is connected to a floating lever *e'*, to which the two levers E and E' are connected. Both the sig-

nals B and B' may therefore be moved to three positions, as indicated by the figures, and as the operation is precisely the same as already described with relation to the signal B' and levers D and D' it is unnecessary to repeat it.

What I claim as my invention is—

1. The combination of a plurality of signals, a plurality of signal-operating levers, and a single line of connections between all of the levers and all of the signals.

2. The combination of a plurality of signals, a plurality of signal-operating levers, and a single line of connections between all of the levers and all of the signals, and operating to move each signal to a plurality of positions.

3. The combination of a plurality of signals, a plurality of signal-operating levers, and a single line of connections between all of the levers and all of the signals, said connections including a floating lever, and rack-bars and pinions.

4. The combination of a plurality of operating-levers, a plurality of signals, a floating lever connected to both signals, a rack-bar connected to the floating lever, a pinion engaging said rack-bar, and means operated by the levers for turning the pinion about its axis in either direction.

5. The combination of a plurality of signals, a plurality of operating-levers, two rack-bars respectively connected to the respective levers to be moved in opposite directions, a floating pinion engaged by both rack-bars, and means for connecting the pinion to all the signals.

6. The combination of a plurality of signals, a plurality of operating-levers, two oppositely-acting bell-crank levers respectively connected to the respective levers, rack-bars connected to the crank-levers, a floating pinion between the rack-bars, and connections between the pinion and all the signals for moving each of said signals to a plurality of positions.

7. The combination of two signals supported on a post, a plurality of operating-levers, two bell-crank levers connected respectively to the respective levers, two rack-bars connected to the bell-cranks, a floating pinion engaged by both rack-bars, a rack-bar connected to the floating pinion, a pinion supported to turn adjacent to the signal-post and engaged by the last-named rack-bar, a vertically-moving rack-bar also engaging the last-named pinion, a floating lever connected between its ends to the vertically-moving rack-bar, and connections between the ends of the floating lever and the signals.

8. The combination of two signals, a plurality of signal-operating levers of which two operate to control one signal, and the remainder to control the other signal, and a single line of connections between all of the levers and both signals.

9. The combination of two signals, a plu-

rality of signal-operating levers of which two operate to control one signal and the remainder to control the other signal, a floating lever connected to the said two levers, two rack-bars, one connected to the floating lever and the other to the remainder of the operating-levers, a floating pinion engaged by both rack-bars, and connections between the floating pinion and both signals, whereby one of said signals may be moved by the operating-levers

to three different positions and the other signal to at least two different positions.

In testimony whereof I have signed my name to this specification in the presence of two subscribed witnesses.

FRANK P. J. PATENALL.
